INVENTOR:
FRANK J. LASAR
by Arthur L. Sles.

UNITED STATES PATENT OFFICE

FRANK J. LASAR, OF SAN FRANCISCO, CALIFORNIA, ASSIGNOR TO CHAMPION WASHER COMPANY, LTD., A CORPORATION OF NEVADA

WASHING MACHINE

Application filed October 28, 1929. Serial No. 403,010.

My invention relates to improvements in washing machine construction wherein an agitator shaft, slidably mounted through a power driven gear, is slidably movable to operative or disengaged relation to the gear whereby the power may be connected and disconnected from said shaft at will while the machine is in operation, said shaft and its agitator being entirely removable when desired.

The primary object of my invention is to provide an improved washing machine.

Another object is to provide an improved means for connecting a power actuated driving mechanism to an oscillating agitator.

A further object is to provide an improved device wherein an agitator actuating shaft may be connected and disconnected while the machine is in operation.

Another object is to provide an improved device of the character described of extremely simple and efficient construction and operation which may be easily and conveniently operated.

A still further object is to provide an improved construction which will facilitate the placing and removal of an agitator for operation within a wash tray, and which will permit the agitator to be disconnected and left idle while the driving mechanism is in operation.

I accomplish these and other objects by means of the improved device disclosed in the drawings forming a part of the present application wherein like characters of reference are used to designate similar parts throughout the specification and drawings and in which,

Fig. 1 is a front elevation of my improved washing machine construction as mounted for operation;

Fig. 2 is a transverse vertical section of the mounting arm and driving connections of my improved agitator actuating means;

Fig. 3 is a broken longitudinal vertical section of the mechanism as shown in Fig. 2 and at right angles thereto;

Fig. 4 is a plan view of the shaft retaining latch mechanism;

Fig. 5 is a transverse sectional detail show-

ing the agitator shaft in operative engagement with its driving gear; and

Fig. 6 is a similar sectional detail showing the shaft in disengaging relation to said gear.

Referring to the drawings, the numeral 1 is used to designate in general a washing machine driving mechanism of any suitable form, preferably of the type mounted upon a wall 2 above a stationary wash tray 3 and driven by a suitable electric motor 4. The machine is preferably provided with the usual wringer mechanism 6 actuated by the driving mechanism 1.

The machine 1 is provided with an agitator mounting arm 7 projecting forwardly from the body of the machine 1 to a point above the wash tray 3. The arm 7 is provided with a suitable crank shaft 8 connected to the driving means and actuated thereby in the ordinary and well known manner to impart an oscillating movement thereto. As the specific mechanism by which the shaft 8 is actuated forms no part of the present invention, and as any of a number of well known expedients may be resorted to to accomplish this action, no detailed disclosure of such connections is herein necessary, and such detailed disclosure is therefore omitted.

The outer end of the arm 7 is recessed as at 9 to form a gear housing into which the shaft 8 extends. A segment gear 11 is secured upon the end of the shaft 8 to oscillate with said shaft. An agitator gear 12 is mounted within the housing recess 9 in meshing relation with the segment gear 11, said gear 12 being provided with a hollow bushing extension 13 journaled within the bottom portion of the arm 7 and also provided with a hollow upwardly extending sleeve portion 14.

The bushing extension 13 is provided with an inwardly disposed shoulder 16 having an opening 17 therethrough to slidably engage an agitator shaft 18 extending axially through the gear 12 and the end of the arm 7. The shaft 18 is shaped to normally prevent rotation of the gear 12 thereon; said shaft preferably being made square in cross section to move longitudinally through the opening 17. The shaft is provided with a reduced

100

portion 19, preferably turned down to a round cross-section of a size adapted to be rotatable within the square opening 17 of the gear 12.

5 A collar 21 is secured upon one end of the shaft. The collar is rotatably received within a sleeve member 22 forming a bearing within the upper part of the arm 7. The collar 21 has its ends beveled as at 23 and 24, and an 10 annular groove 26 is formed in the collar intermediate the beveled ends 23 and 24. The collar 21 is made of sufficient length to form a substantial bearing at the top of the shaft, while the bushing extension 13 forms a bearing spaced from said collar whereby the shaft 15 is effectually supported when in operation. The collar 21 is adapted to seat against the upper end of the extension 14 to limit the downward movement of the shaft 18 through 20 the gear 12.

A retaining latch member 27 is pivotally mounted as at 28 upon the top of the arm 7 and arranged to be moved through a transverse slot 28 formed in the bearing sleeve member 22 to engage the groove 26 of the collar 21. The member 27 is shaped to fit into the groove 26 along a substantial area and permit rotation of the collar 22 relative to the member 27. A spring actuated plunger 29 25 engages the latch member 27 to normally hold said member in operative engagement with the collar 21, said member 27 being movable against the tension of the plunger spring 31 by pressure exerted manually upon a lever 30 portion 32 formed upon the free end of the latch member.

A reduced extension 33 is formed upon the upper end of the shaft 18. A knob 34 is rotatably mounted upon the extreme top of the 40 extension 33, said extension and knob extending upwardly to a point spaced above the top of the sleeve member 22.

In operation, the shaft 18 is moved downwardly through the sleeve member 22 and the 45 gear 12 with its extensions 13 and 14, the shaft being normally held against rotation by its engagement with the opening 17. As the shaft 18 is moved into operative position, the lower end of the shaft is moved to engage an 50 agitator 35 provided with agitator blades or vanes 36 and having an upwardly extending stem 37 having an axial opening therethrough to slidably engage the end of the shaft 18, the opening being shaped to substantially conform to the shape of the shaft 55 to impart movement from the shaft to the agitator. The stem 37 is made of sufficient length to permit the agitator to be raised or lowered a substantial distance relative to the shaft 18 without reducing the effectiveness of the driving connection between the shaft and the agitator.

As the shaft 18 is moved downwardly to 60 operative position, the lower beveled edge 23 of the collar 21 forces the latch member 27

outwardly to admit the collar 21 therewith. When the groove 26 reaches a point opposite the latch member 27, said latch member is moved inwardly into engagement with the groove, thereby holding the collar and shaft against further downward movement until the latch is moved to disengage the groove. The groove 26 and the reduced portion 19 of the shaft are so positioned relative to each other and relative to the latch member 27 and the shouldered portion 16 that when the shaft is supported by means of the latch 27 and the groove 26, the reduced portion 19 of the shaft will be held within the shouldered portion 16 of the gear, thereby permitting the gear 12 to be moved without imparting movement to the shaft.

By releasing the latch member 27, the shaft 18 may be moved further downwardly to the position shown in Fig. 2 of the drawings, thereby moving the square portion of the shaft into engagement with the shouldered portion 16 of the gear, and causing said shaft to be actuated by and with the gear. Thus, when the gear 12 is oscillated by the operation of the segment gear 11, the shaft 18 will be correspondingly oscillated, and the shaft will operate to oscillate the agitator 35 with a corresponding movement.

To stop the shaft 18 and agitator 35, the 95 shaft 18 is moved upwardly by means of the extension 33 and knob 34 to the position shown in Fig. 3. The knob 34 being rotatable upon the extension 33, permits the shaft to be lifted manually while the shaft is in motion 100 without danger of injury to the operator. As the shaft is thus lifted, the beveled edge 24 of the collar 21 forces the latch member 27 outwardly to clear the collar. As the reduced portion 19 of the shaft is moved to 105 match with the shoulder 16, the latch 27 is moved by the plunger 29 to again engage the groove 26, thereby supporting the shaft in a position disengaged from the gear 12. The driving mechanism 1 may now be kept in 110 operation for actuating the wringer or for other purposes, without imparting movement to the shaft 18 and the agitator 35.

From the position shown in Fig. 3 of the 115 drawings, the shaft may be released to drop back to operative driving position as shown in Fig. 2, or it may be moved upwardly and entirely withdrawn from the arm 7, thereby permitting the agitator 35 to be removed 120 from the tray to afford clear and unobstructed access to the tray. To facilitate the withdrawal of the shaft 18, the lower edge of the latch member 27 is beveled as at 38, whereby pressure applied to the knob 34 to move the shaft upwardly will operate to force the latch member to disengage the groove 26. By turning the lever portion 32 manually, the latch member 27 may be moved to release the shaft 125 and permit it to be moved downwardly by gravity to its normal operative position.

The shaft 18 is chamfered, as at 39, at the corners adjacent the reduced portion 16 to facilitate the movement of the square portion of the shaft into the aperture 17. As the gear 12 is oscillated by the segment gear 11, the chamfered corners 39 move freely into the aperture 17 when said aperture is moved to register with the shaft.

The gears 11 and 12 are lubricated by suitable lubricant supplied into the gear housing recess 9, said lubricant being effectually retained within the housing recess by means of cover plates 41 and 42 secured upon the outer end of the arm and upon the bottom of the arm respectively, as best shown in Fig. 3 of the drawings.

Having thus described my invention, what I claim as new and desire to secure by Letters Patent is:

- 20 1. In a washing machine, the combination with a power driven oscillating crank shaft and an agitator gear actuated thereby, of a shaft slidably mounted axially through the gear, said shaft being of non-circular cross section and engaging an opening of corresponding shape formed axially through the gear to normally prevent relative rotation between said shaft and gear, said shaft having a reduced portion moved into relatively rotatable engagement with the gear, the greatest diameter of said reduced portion being less than the shortest diameter of the axial gear opening whereby the gear may be rotated relative to the shaft upon that portion, means for moving the shaft axially to move the reduced portion into engagement with the gear to release the shaft from said gear; and means for releasably holding said shaft in the gear disengaging position.
- 25 2. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear whereby the gear may be rotated independently of the shaft; and a latch member movable to engage an annular groove carried by the shaft to hold the shaft in gear releasing position said latch member being movable to release the shaft for movement axially into operative engagement with said gear.
- 30 3. In a washing machine, the combination with a power driven oscillating crank shaft and an oscillator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear whereby the gear may be rotated independently of the shaft; a latch member movable to engage an annular groove carried by the shaft to hold the shaft in gear releasing position said latch member being movable to release the shaft for movement axially into operative engagement with said gear.
- 35 4. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; and a latch member pivotally mounted adjacent the collar and movable to engage the groove of said collar to retain the shaft in gear releasing position.
- 40 5. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; a latch member pivotally mounted adjacent the collar and movable to engage the groove of said collar to retain the shaft in gear releasing position; and a rotatable knob mounted upon the shaft whereby the shaft may be moved to gear disengaging position while the machine is in operation.
- 45 6. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; a latch member pivotally mounted adjacent the collar and movable to engage the groove of said collar to retain the shaft in gear releasing position, said member being 130

with the gear whereby the gear may be rotated independently of the shaft; a latch member movable to engage an annular groove carried by the shaft to hold the shaft in gear releasing position said latch member being movable to release the shaft for movement axially into operative engagement with said gear; and a rotatable knob mounted upon the shaft whereby said shaft may be moved to disengaging position while the machine is in operation.

70 75 80 85 90 95 100 105 110 115 120 125 130

4. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; and a latch member pivotally mounted adjacent the collar and movable to engage the groove of said collar to retain the shaft in gear releasing position.

5. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; a latch member pivotally mounted adjacent the collar and movable to engage the groove of said collar to retain the shaft in gear releasing position; and a rotatable knob mounted upon the shaft whereby the shaft may be moved to gear disengaging position while the machine is in operation.

100 105 110 115 120 125 130

6. In a washing machine, the combination with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear in one direction, said collar having beveled ends and an annular groove intermediate said ends; a latch member pivotally mounted adjacent the collar and movable to engage the groove of said collar to retain the shaft in gear releasing position, said member being 130

adapted to be displaced by the beveled ends of the collar when moved in either direction past said member.

7. In a washing machine, the combination 5 with a power driven oscillating crank shaft and an agitator gear actuated thereby, of an agitator shaft slidably mounted through the gear and removable through one end thereof, said shaft being shaped to normally prevent relative rotation between the gear and shaft and having a reduced portion movable into relatively rotatable engagement with the gear; a collar secured upon the shaft to limit movement of the shaft through the gear 10 in one direction, said collar having beveled ends and an annular groove intermediate said ends; a latch member pivotally mounted adjacent the collar and movable to engage the groove of said collar to retain the shaft in gear releasing position, said member being 15 adapted to be displaced by the beveled ends of the collar when moved in either direction past said member; and resilient means normally holding the latch member in engagement 20 with the shaft and collar.

8. A washing machine comprising a power actuated driving mechanism; an arm mounted adjacent the driving mechanism; an oscillating crank shaft mounted within the 25 arm and actuated by the driving mechanism; a segment gear mounted upon the shaft within the outer end of the arm; an agitator gear mounted within the outer end of the arm in meshing relation with the segment gear; an 30 agitator shaft slidably mounted through the end of the arm and through the agitator gear, said shaft being removable upwardly through the arm and gear and being shaped to normally prevent relative rotation between 35 said shaft and gear; a reduced portion formed upon the shaft movable into rotatable engagement with the gear whereby the shaft is rotated within the gear when said portion is moved into engagement with the gear; a collar mounted upon the upper end of the shaft 40 and limiting the downward movement of the shaft through the gear and arm, said collar having an annular groove; and a latch member mounted upon the arm and movable to engage the groove to hold the shaft in gear 45 disengaging position, and movable to release the shaft for downward movement to operative position.

9. A washing machine comprising a power 55 actuated driving mechanism; an arm mounted adjacent the driving mechanism; an oscillating crank shaft mounted within the arm and actuated by the driving mechanism; a segment gear mounted upon the shaft within 60 the outer end of the arm; an agitator gear mounted within the outer end of the arm in meshing relation with the segment gear; an agitator shaft slidably mounted through the end of the arm and through the agitator 65 gear, said shaft being removable upwardly

through the arm and gear and being shaped to normally prevent relative rotation between said shaft and gear; a reduced portion formed upon the shaft movable into rotatable engagement with the gear whereby the shaft 70 is rotated within the gear when said portion is moved into engagement with the gear; a collar mounted upon the upper end of the shaft and limiting the downward movement of the shaft through the gear and arm, said 75 collar having an annular groove; a latch member mounted upon the arm and movable to engage the groove to hold the shaft in gear disengaging position, and movable to release the shaft for downward movement to operative 80 position, said collar also having beveled ends to displace the latch member when the collar is moved in either direction therepast.

10. A washing machine comprising a power actuated driving mechanism; an arm 85 mounted adjacent the driving mechanism; an oscillating crank shaft mounted within the arm and actuated by the driving mechanism; a segment gear mounted upon the shaft within the outer end of the arm; an agitator gear mounted within the outer end of the arm in meshing relation with the segment gear; an 90 agitator shaft slidably mounted through the end of the arm and through the agitator gear, said shaft being removable upwardly through the arm and gear and being shaped to normally prevent relative rotation between 95 said shaft and gear; a reduced portion formed upon the shaft movable into rotatable engagement with the gear whereby the shaft is rotated within the gear when said portion is moved into engagement with the gear; a collar mounted upon the upper end of the shaft and limiting the downward movement of the shaft through the gear and arm, said collar having an annular groove; a latch member mounted upon the arm and movable to engage the groove to hold the shaft in gear disengaging position, and movable to release the shaft for downward movement to operative 100 position, said collar also having beveled ends to displace the latch member when the collar is moved in either direction therepast; and a rotatable knob mounted upon the upper end of the shaft 105 whereby the shaft may be moved to operative and disengaged positions as desired while the machine is in operation.

In witness whereof, I have hereunto set my signature.

FRANK J. LASAR.
